UNITED STATES PATENT OFFICE.

WALTER H. THOMAS, OF SPENCER, IOWA.

FOOT-ACCELERATOR.

1,276,829.

Specification of Letters Patent. Patented Aug. 27, 1918.

Application filed April 1, 1915. Serial No. 18,575.

To all whom it may concern:

Be it known that I, WALTER H. THOMAS, a citizen of the United States, residing at Spencer, within the county of Clay and State of Iowa, have invented a new and useful Foot-Accelerator, of which the following is a specification.

My invention is intended for automobiles equipped only with a hand throttle lever and provides means for controlling the speed of the motor by the foot independently of the hand and has for its objects; a greater convenience for the driver; a more perfect control of the machine; and a larger degree of safety for the occupants of the car.

These objects I attain by the mechanism illustrated in the accompanying drawing in which—

20 Figure I is a view of the accelerator as attached to a Ford motor car with part of one cylinder broken away to show the carbureter and its connecting rod; and Figs. II, III, IV, and V, are merely details of the 25 more important parts in the mechanism.

Similar numerals refer to similar parts throughout the several views.

In this accelerator the pedal 7, which is operated by the driver's foot, is connected 30 to one end of the rod 4, while the other end is connected to the offset end of the angle 3, which in turn is pivoted to one end of the bracket 5 by means of the pin 6. The bracket 5 may be attached to any convenient place, say the waterjacket outlet of 35 the motor. One end of the rod 1 is made to slide in an opening in angle 2 and is connected to the other arm of the angle 3 by means of the shoulder hook 10 while its 40 other end is connected to carbureter lever 11 which operates the throttle within the carbureter. The other end of the angle 2 is connected by means of the pin 8 to the arm 9 which is located upon the throttle 45 rod 14 of the machine. The springs 12 and 13 serve to keep the throttle closed or to close it after either the hand or foot control or both are released.

The device operates as follows: pressing 50 the pedal 7 with the foot causes the angle 3 to rotate about the pin 6 which in turn draws the rod 1 toward the angle 2 at the same time rotating the lever 11, which as before stated operates the throttle, and 55 opens it, thus admitting more gas to the

motor. If the pedal 7 is partly or wholly released the throttle is closed in the same proportion and the gas is shut off in the same degree. Since the speed of the motor varies as the amount of gas admitted it can 60 readily be seen that the speed will be increased or decreased as the throttle is opened or closed. The fact that the rod 1 is permitted to slide toward the left in the angle 65 2 enables the foot accelerator to be used independently of the hand control. When the hand control is used the angle 2 is brought up against the shoulder hook 10 by means of the arm 9 and rod 14. As this arm 9 is moved it carries with it the angle 2 70 and the rod 1, opening or closing the throttle as before described.

Manifestly the rod 1 is free to move through the inner arm of the angle 2 without movement of said angle. When, however, the rod 14 is thrust forwardly to move the arm 9 and the outer arm of the angle 2 forwardly, the angle 2 will be rocked on its apex which bears against a part of the engine, as shown in Fig. I, and the inner arm 80 of the angle, abutting against the shoulder hook 10 will move said hook and the rod 1 to rotate the lever 11 for the purpose before stated.

Having thus described and shown the 85 construction and operation of my invention,

I claim—

1. In means for the purpose described, the combination of an internal combustion engine, a carbureter connected therewith and having a lever, a suitably mounted bell-crank, a rod extending between and connecting the carbureter lever and one arm of said bell-crank and having an abutment, a rod connected to and extending rearwardly from the other arm of the bell-crank, an angle mounted to swing on its apex and loosely receiving in one of its arms the said connecting rod and having said arm arranged against the abutment on 95 the rod and between said abutment and the throttle lever, spring means for closing the throttle, and a rearwardly extending rod connected to the other arm of the angle.

2. In means for the purpose described, 105 the combination of an internal combustion engine, a carbureter connected therewith and having a lever, a suitably mounted bell-crank, a cross rod extending between and connecting the carbureter lever and one arm 110

of the bell-crank and movable by the bell-crank, a rod connected to and extending rearwardly from the other arm of the bell-crank, an angle mounted to swing on its 5 apex and having one of its arms arranged to move the cross-rod without interfering with the movement of said rod by the bell-

crank, spring means for closing the throttle, and a rearwardly extending rod connected to the other arm of the angle.

WALTER H. THOMAS.
